UNITED STATES PATENT OFFICE

156,983

FISHING ROD

John D. McMillan, Muskegon Heights, Mich., assignor to Champion Products Company, Muskegon Heights, Mich., a corporation of Michigan

Application May 9, 1949, Serial No. 2,530

Term of patent 14 years

(Cl. D31—4)

To all whom it may concern:

Be it known that I, John D. McMillan, a citizen of the United States, residing at Muskegon Heights, in the county of Muskegon and State of Michigan, have invented a new, original, and ornamental Design for a Fishing Rod, of which the following is a specification, reference being had to the accompanying drawing, forming part thereof.

Fig. 1 is a plan view of a fishing rod, showing my new design.

Fig. 2 is a side view of the same, and

Fig. 3 is a bottom view of the same.

I claim:

The ornamental design for a fishing rod, substantially as shown.

JOHN D. McMILLAN.
